UNITED STATES PATENT OFFICE.

JEREMIAH A. SCRIVEN, OF NEW YORK, N. Y.

DESIGN FOR A BIFURCATED NETHER GARMENT.

SPECIFICATION forming part of Design No. 31,772, dated October 31, 1899.

Application filed October 5, 1899. Serial No. 732,729. Term of patent 14 years.

To all whom it may concern:

Be it known that I, JEREMIAH A. SCRIVEN, a citizen of the United States, residing in the city, county, and State of New York, (post-office address No. 18 East Fifteenth street,) have invented and produced a new and original Design for Bifurcated Nether Garments, of which the following is a specification.

The characteristic feature of my design consists in elongated insertions or panels let into the garment, each of said panels extending from substantially the upper end and on one side of the garment to substantially the lower end on the other side thereof.

5 In the accompanying drawings, Figure 1 is a front view of a nether garment embodying my design. Fig. 2 is a rear view of the same.

A represents the body portion of a nether garment, from which extend tubular members

B. Let into the garment are elongated panels 20 or insertions C, each of which extends from substantially the upper end of the garment and on one side thereof, as indicated at a, to substantially the lower end of a tubular member and upon the opposite side of the 25 garment, as indicated at b. Each of the panels in passing from one side to the other of the garment or from front to rear thereof passes spirally around a tubular member B. The ribs or wales c of each insertion or panel 30 C extend in a longitudinal direction.

What I claim is--

The design for a bifurcated nether garment, substantially as herein shown and described.

JEREMIAH A. SCRIVEN.
